UNITED STATES PATENT OFFICE.

RAYMOND B. HARPSTER, OF HEPLER, AND JOHN J. GEES, OF WALNUT, KANSAS.

WALL-PAPER-MEASURING DEVICE.

1,076,034.

Specification of Letters Patent.

Patented Oct. 21, 1913.

Application filed June 7, 1912. Serial No. 702,249.

To all whom it may concern:

Be it known that we, RAYMOND B. HARPSTER and JOHN J. GEES, citizens of the United States, residing at Hepler and Wal-

5 nut, respectively, in the county of Crawford and State of Kansas, have invented new and useful Improvements in Wall-Paper-Measuring Devices, of which the following is a specification.

10 This invention relates to wall paper measuring devices, and has for an object to provide a device of this character which can be readily applied to slitting apparatus, whereby as the paper is unwheeled and 15 wound from one roll to another it may be accurately measured.

Another object of the invention is to provide apparatus of this character which will include means for yieldingly holding the 20 actuating element of the indicator against the magazine or initial roll of paper.

Another object of the invention is to provide a measuring device which will be adjustable with relation to the roll supporting shaft, so as to permit of the convenient 25 attachment to and detachment of the roll from the shaft.

In the drawings: Figure 1 is a longitudinal section of a slitting apparatus, showing 30 the application of the measuring device thereto. Fig. 2 is a similar view, showing the slitting device adjusted to an inoperative position. Fig. 3 is a plan view of a portion of the slitting apparatus and a portion 35 of the measuring device.

The slitting apparatus, conventionally shown at 1 herein, includes a support or platform 2, on which is mounted the usual shaft 3 for supporting a roll of paper, and a 40 winding or receiving shaft 4, on which the paper, as it is cut and measured, may be wound. The slitting apparatus also includes a supporting table 5, which is located in such proximity to the companion shearing 45 knives 6 as to compel an accurate travel of the paper between the knives, as is understood.

The measuring device which is designed 50 to measure the paper as it is cut by the companion shearing knives 6, includes a casing 7 which is hinged for vertical adjustments upon the platform or base 2, as shown at 8. The point of hinge connection of the casing is preferably disposed at one side of and 55 parallel with the roll holding shaft 3, so that the casing, when in an operative posi-

tion, will be substantially tangential thereto, with a resultant periphery engagement of the actuating wheel 9 of the device with the roll of paper.

The shaft 10 which supports the actuating wheel 9 has secured thereto a relatively large gear wheel 11 which meshes with a small gear wheel 12 forming one element of a gear train 13, the wheel 14 of the train being mounted to the shaft 15 which extends through the walls of the casing 7, and which supports a pointer 16 which coacts with a measuring dial surface 17 of the casing. This surface is concentrically disposed with 60 relation to the shaft 15, whereby the pointer is compelled to travel thereover when power is applied thereto, through the intermeshing gearing hereinabove described. The actuating wheel 9 of the device extends through 65 a slot 18 in one of the walls of the casing 7, and it is adapted for peripheral engagement with the roll A upon the shaft 3, whereby as the latter is revolved to unwind 70 the roll and to feed the paper in the direction of the slitting knives, the element 9 will be controlled to influence the pointer 16 and to definitely determine the length of paper 75 unwound. With a view to operatively holding the element 9 properly associated with the roll A, I provide the table portion 5 of the slitting apparatus with one or more hooks 20, over which may be extended the elastic element 21 of the casing 7. When it 80 is desired to supply the slitting apparatus with a new roll of paper, the elastic element 21 is disconnected from the hooks 20, whereupon the casing 7 can be swung to the 85 position shown in Fig. 2, thus giving access 90 to the shaft 3, as is appreciated.

95 What is claimed is:

1. The combination with slitting apparatus, including a platform support for rolled merchandise, a table in advance of the support, of a measuring device, including a 100 pivotally mounted casing adapted for movement above and below the plane of the top of the table and having one of its walls formed with a slot, a revolvably mounted actuated element disposed within said casing 105 and having its peripheral surface extended through the slot and beyond the outer face of the rear wall of the casing and adapted to contact with the roll of merchandise, the said casing having a dial thereon, a pointer 110 contacting with the dial, means connected to the outer face of the side walls of the cas-

ing and to the table for holding the actuating element yieldingly in contact with the roll and controlling means between the actuating element and the pointer.

- 5 2. The combination with slitting apparatus, including a platform support for rolled merchandise, and a table in advance of the support having hooks along its front transverse edge, of a measuring device, said
10 measuring device being provided with means for adjusting the same above and below the plane of the table, said means including

elastic elements carried by the opposite sides of the measuring device for engagement with the hooks disposed along the front 15 transverse edge of the table.

In testimony whereof we affix our signatures in presence of two witnesses.

RAYMOND B. HARPSTER.
JOHN J. GEES.
